(57) **CLAIM**

The ornamental design for a lamp, as shown and described.

DESCRIPTION

FIG. 1 is a top perspective view of my new design for a lamp;

FIG. 2 is a bottom perspective view of my new invention;

FIG. 3 is a left side elevation view of my new invention;

FIG. 4 is a rear elevation view of my new invention;

FIG. 5 is a right side elevation view of my new invention;

FIG. 6 is a front elevation view of my new invention;

FIG. 7 is a bottom plan view of my new invention;

FIG. 8 is a top plan view of my new invention;

FIG. 9 is a bottom plan view of my new invention with a
carabineer clip open and a crank extended;

FIG. 10 is a top plan view of my new invention with the
carabineer clip open and the crank extended;

FIG. 11 is a left side elevation view of my new invention
with the carabineer clip open and the crank extended;

FIG. 12 is a rear elevation view of my new invention with
the carabineer clip open and the crank extended;

FIG. 13 is a right side elevation view of my new invention
with the carabineer clip open and the crank extended;

FIG. 14 is a front elevation view of my new invention with
the carabineer clip open and the crank extended; and,

FIG. 15 is a top perspective view of my new invention with
the carabineer clip open and the crank extended.

The broken lines shown represent unclaimed portions of the
article and form no part of the claimed design.

1 Claim, 8 Drawing Sheets
